DESIGN FOR A HAIR WAVING MACHINE

Fernan O. Conill, New York, N. Y.

Application September 23, 1936, Serial No. 64,966

Term of patent 14 years

To all whom it may concern:

Be it known that I, Fernan O. Conill, a citizen of Cuba, residing at New York, New York, have invented a new, original, and ornamental Design for a Hair Waving Machine, of which the following is a specification, reference being had to the accompanying drawing, forming part thereof.

The figure is a perspective view of a hair waving machine, showing my new design.

The other side of the machine shown in the drawing is of substantially the same configuration as the side shown, with the exception that the support arm is omitted.

I claim:

The ornamental design for a hair waving machine, as shown and described.

FERNAN O. CONILL.
